UNITED STATES PATENT OFFICE.

WILLIAM L. GILMORE, OF MINEOLA, NEW YORK, ASSIGNOR TO CURTISS AEROPLANE & MOTOR COMPANY, INC., OF GARDEN CITY, LONG ISLAND, A CORPORATION OF NEW YORK.

AEROPLANE WING.

Application filed August 30, 1924. Serial No. 735,078.

To all whom it may concern:

Be it known that I, WILLIAM L. GILMORE, a citizen of the United States, residing at Mineola, L. I., in the county of Nassau and State of New York, have invented certain new and useful Improvements in Aeroplane Wings, of which the following is a specification.

My invention relates to aerofoils for aircraft and more particularly to improvements in the method and manner of covering aeroplane supporting surfaces or wings.

The practice, heretofore, in the construction of aerofoils, has been to provide either a wood or metal framework of predetermined profile, and over such framework fasten, by any appropriate means, a suitable covering; such covering being formed either of fabric, veneer or metal, the choice of material depending primarily upon the character of the framework employed. Each of the above mentioned materials, as an aerofoil covering, has its particular advantages and disadvantages. Fabric, while extremely light and comparatively inexpensive, is effected by weather conditions, and must periodically, at least, be renewed. Metal or veneer, on the other hand, and especially metal, while heavy as compared to fabric, and more expensive, is nevertheless very often desirable as a covering material in view of its inherent strength, as well as its ability to withstand hard usage without rapid deterioration under varying weather conditions.

The object of the present invention is to effect a compromise upon the advantages and disadvantages of the now used covering materials; retaining in so far as possible the advantages of both and at the same time eliminating the known disadvantages. In effecting this compromise it is proposed to provide, (1) a skeleton framework of conventional design (2) a top covering of metal in which the covering material is carried respectively to the leading edge and the trailing edge of the framework, and (3) an under or bottom covering of fabric. In thus using metal and fabric; metal, which is inherently strong, serviceable and lasting, is used where greatest strength, serviceability and longevity are required, i. e., upon that surface of the aerofoil wholly unprotected against the elements, whereas fabric, which is more or less effected by the weather and which can be cheaply and quickly removed

and renewed should inspection or repair of the framework be required, is used where protection against the elements is at all times afforded by the metal top covering itself. An aerofoil thus characterized has the advantages of a fabric covered aerofoil in part and of a metal covered aerofoil in part, whereas the inconveniences and disadvantages of both are to a large degree eliminated.

Other objects, advantages and improved results will be hereinafter set forth.

In the drawings, wherein like reference characters denote like or corresponding parts throughout the several views,

Fig. 1 is a view in transverse section of an aeroplane wing showing the framework construction as well as the manner in which the covering therefor is disposed;

Fig. 2 is a similar view showing only a portion of the wing, somewhat enlarged;

Fig. 3 is a fragmentary view, in front elevation, of a portion of the wing showing the method and manner in which the under fabric covering for the framework is fastened;

Fig. 4 is a fragmentary sectional view of a portion of an aerofoil showing the manner in which the metal covering is fastened, and

Figs. 5 and 6 are views similar to Fig. 4 showing slightly modified forms of cover fastening.

In the embodiment of the invention selected for illustration an aeroplane wing or supporting surface of conventional profile is shown. Said wing or supporting surface comprises a forward wing beam 10, a rear wing beam 11, a multiplicity of ribs 12, a leading edge strip 13 and a trailing edge strip 14, all of said parts, as herein illustrated, being of metal construction and collectively constituting a skeleton framework over which the covering for the wing is disposed. Preferably beams 10 and 11, and the ribs 12 are of trussed construction tho they may be, of course, constructed of wood or any other material and formed differently than herein shown. Upon the top surface of the framework a metal outer covering 15 is laid. Said outer covering preferably comprises a plurality of metal strips (aluminum or one of its alloys being preferred) arranged in overlapping relation and riveted in place as at 16 to the ribs 12 as illustrated in Fig. 4. These metal strips or

sheets 15 are carried in a fore and aft direction to the leading edge and to the trailing edge respectively of the wing. At the leading edge the top metal covering is extended over and slightly under the nose of the wing to the end that the entering portion thereof may be strongly reinforced. At the trailing edge of the wing the metal covering is similarly arranged whereby at the trailing edge the metal covering is carried over and under the trailing edge strip 14. Metal covering thus used not only lends added strength to the wing but it moreover affords a rigid covering for the framework unaffected to any appreciable extent by the elements.

Instead of providing a similar covering for the under surface of the wing, fabric 16 is used. The under surface of the wing, unlike the top surface thereof, is seldom exposed to the hard wear and rough usage usually encountered by the top covering of the wing, and it is for this reason, together with the fact that fabric is less expensive, that fabric is employed as herein shown. Furthermore, it has been found in practice, that in covering an aeroplane wing entirely with metal, great inconvenience and annoyance is encountered when inspection or repair of the framework is required. In substituting fabric for metal as the bottom covering, this inconvenience and annoyance is almost entirely eliminated by reason of the fact that the fabric covering may be removed quite easily and replaced at will. Fabric, moreover, being more or less fragile and injuriously effected by the elements, is only used as a covering throughout that portion of the wing where greatest protection is at all times afforded.

At the leading edge and at the trailing edge of the wing the fabric covering 16 laps the metal covering 15 where it is first fastened by gluing or by any other suitable means and where such fastening is reinforced by a fabric strip 17 doped and glued over the overlapping portion as indicated in Fig. 3. In Figs. 5 and 6, slightly modified forms of top metal covering are shown. In Fig. 5 the sheets of metal are riveted to the framework as at 18 and to each other as at 19, the adjacent edges of juxtaposed sheets being interlocked by carrying the edge of one of said sheets over and upon the upturned edge of the other. In Fig. 6 the fastening is the

same as indicated in Fig. 4, the only difference being that the metal sheets are corrugated as at 20 instead of being flat as indicated in connection with the preferred arrangement of Fig. 4.

The advantages of a wing characterized as above set forth are many fold. In using metal as the top covering that portion of the aerofoil wholly exposed to the elements and subject to the hardest usage is amply protected due to the inherent qualities of the metal itself. In limiting the use of fabric to the bottom surface only of the framework, protection is afforded the fabric against the elements while at the same time the advantages of fabric as a covering are retained.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What I claim is:

1. An aeroplane wing including a skeleton framework, a top covering of metal carried respectively to the leading edge and to the trailing edge of the wing, and an under covering of fabric likewise carried respectively to the leading edge and to the trailing edge.

2. An aeroplane wing including a skeleton framework, a top covering of metal carried over and under both the leading edge and the trailing edge of the wing, and an under covering of fabric having its front and rear edges respectively fastened to the corresponding edges of the metal covering.

3. An aeroplane wing including a skeleton framework, a top covering of metal for the framework having its front edge and its rear edge lapped over and under the leading edge and the trailing edge respectively of the wing, and an under covering of fabric having its front and its rear edge lapped over and upon the corresponding edges of the metal covering, where it is fastened.

In testimony whereof I hereunto affix my signature.

WILLIAM L. GILMORE.
